UNITED STATES PATENT OFFICE

2,049,708

REFRIGERATOR

Gustav Lieb, Stuttgart, Germany, assignor to
 Robert Bosch Aktiengesellschaft, Stuttgart,
 Germany

Application December 12, 1933, Serial No. 701,993
 In Germany December 14, 1932

2 Claims. (Cl. 62—126)

My invention relates to refrigerators, more especially of the vaporization type. It is an object of my invention to improve the construction of refrigerators of this kind in such manner as to render same more efficient and economical.

5 In refrigerators operated with a refrigerant alternately liquefied and vaporized the cold-producing device evaporator is as a rule arranged within the space designed to take up the food products and beverages to be cooled. This arrangement of 10 the evaporator in the cooling space proper involves the drawback that the space available for the goods to be cooled is considerably diminished, while at the same time the temperature in different parts of the cooling space is not uniform.

15 It has already been suggested to avoid these drawbacks by disposing the evaporator in the form of a container or a coiled pipe around the container for the goods to be cooled and rigidly connecting it with this container, for instance by welding. However if the rigidly connected 20 containers are exposed to high temperatures such as required for instance when coating the inner container with enamel, one runs the risk that owing to the inner stresses occurring in the metal at high temperatures the containers may become 25 distorted and the points of connection as well as the boiler itself unfavorably influenced. When subsequently testing the evaporator for resistivity to pressure much waste must be taken into account.

In order to avoid this, I construct the evaporator as a separate unit which is exchangeably mounted on and surrounds the inner container being in heat-conductive metallic connection with it. This evaporator may first be tested and only thereafter united with the container for the goods to be cooled, after this latter has been enameled. I thereby obtain that the costs of construction of 35 a domestic refrigerator are greatly reduced and any danger of the evaporator being damaged in 40 subsequent operations excluded. The evaporator being loosely mounted on the inner container can easily be exchanged. If it is desired to provide for cold-storage, I prefer combining the evaporator with the cold-storer containing the brine or other storing medium so as to form a self-contained unit.

In the drawing affixed to this specification and forming part thereof an embodiment of a refrigerator according to my invention is illustrated diagrammatically by way of example in longitudinal section.

5 In the embodiment illustrated in the drawing the evaporator mounted on the food container *c* consists of two sleeves, a plain cylinder *w* and a spirally corrugated cylinder *x* forming between them the spiral conduit *f* acting as evaporator. *y* is a cylindrical shell united with the inner sleeve *w* and spaced from the corrugated sleeve *x*, the space *z* between them being filled with brine. *g* and *h* are the feed and discharge pipes, respectively, for the refrigerant. The sleeves *w* and *x* and the shell *y* are combined to form a self-contained unit exchangeably mounted on the container *c* in heat-conductive metallic connection therewith. This unit is manufactured and tested independently of the manufacture of the container *c* and therefore is not affected by the operations gone through by this container during its manufacture.

10 I wish it to be understood that I do not desire to be limited to the exact details of construction shown and described for obvious modifications 15 will occur to a person skilled in the art.

20 I claim:—

1. A cooling element for use in a domestic refrigerator comprising an inner cylindrical container for the goods to be cooled, a cylindrical evaporator having an annular chamber therein for refrigerant, snugly but removably fitting around said container whereby a direct metallic path for heat transfer is formed between said container and said evaporator.

2. A cooling element for use in a domestic refrigerator comprising an inner cylindrical container for the goods to be cooled, a cylindrical evaporator having an annular chamber therein for refrigerant, snugly but removably fitting around said container whereby a direct metallic path for heat transfer is formed between said container and said evaporator, and a cold storer combined with said evaporator so as to form with the same a structural unit.

GUSTAV LIEB.
